TEMPERING MEANS FOR SHIELDING
THE BEARINGS OF CENTRIFUGAL
COMPRESSORS

William H. Church, Jersey City, and Max Haeberlein, Maplewood, N. J., assignors to Worthington Pump and Machinery Corporation, Harrison, N. J., a corporation of Delaware

Application October 28, 1948, Serial No. 56,946

4 Claims. (Cl. 230—209)

1

This invention relates to centrifugal compressors and, more particularly the means for shielding the inboard and outboard bearings of a centrifugal compressor from extreme temperature conditions due to their proximity to the compressor casing.

The conditions of service under which a centrifugal compressor will operate may vary from -150° F. to 300° F. at the suction and from -50° F. to 400° F. at the discharge of the compressors. The bearings for the impeller shaft of the compressor, being in close proximity to the casing, will be adversely affected by the extreme temperature conditions of the compressor operating temperatures.

It is an object of the present invention to utilize gas compressed by the compressor, taken from suitable points in the compressor casing and delivered about the compressor shaft between the shaft bearings and the end compressing stages of the compressor to shield or protect the bearings from the extreme temperature conditions occasioned by the compressor operating temperature.

With these and other objects in view, as may appear from the accompanying specification, the invention consists of various features of construction and combination of parts, which will be first described in connection with the accompanying drawings, showing a tempering means for shielding the bearings of centrifugal compressors of a preferred form embodying the invention, and the features forming the invention will be specifically pointed out in the claims.

In the drawings:

Figure 1 is a longitudinal section through the compressor showing the bearing shielding means applied thereto.

Figure 2 is an enlarged detail section illustrating the manner in which the protecting gas is distributed about the shaft.

Referring more particularly to the drawings, a centrifugal compressor of any approved type is shown in longitudinal section and it includes a casing 1 in which are mounted a plurality of compression stages indicated at 2, each of which include a centrifugal compressing impeller 3. The impellers 3 are mounted upon and rotated by an impeller shaft 4 which is rotatably supported by suitable bearing structures 5 and 6. The inboard bearing 5 is located at the suction end of the compressor and in relatively close proximity to the suction inlet 7 of the first stage impeller 3, while the outboard bearing 6 is located at the discharge end of the compressor.

2

The conditions under which centrifugal compressors operate vary widely over temperature ranges, in some conditions operating at suction pressures as low as -150° F. and at others to temperatures as high as 300° F. at the suction, while the temperatures at the discharge end vary from -50° F. to 400° F. These wide temperature ranges adversely affect the bearing structures so that it is desirable to in a measure equalize the temperatures at both the suction and discharge ends of the compressor, about the impeller shaft 4, for shielding the bearing structures from the extreme temperature conditions of compressor operation.

15 For this purpose, means are provided for taking relatively cool gas from any predetermined point within the compressor casing and delivering it about the impeller shaft 4 between the outboard bearing 6 and the final or discharge compression stage of the compressor and to take relatively hot gas from a predetermined point within the compressor casing and deliver it about the impeller shaft 4 at a point between the inboard bearing structure 5 and the first stage impeller 3 of the compressor.

In the drawings a conduit 10 is shown as having its inlet opening into the first compression stage of the compressor at a point in proximity to the discharge of the first stage impeller 3 with its discharge end 11 opening into a distributor or lantern gland 12. The distributor or lantern gland 12 is mounted about the shaft 4 between the outboard bearing 6 and the final stage impeller 3 of the compressor and thus relatively cool gas is fed about the shaft 4 at this point to dissipate or counteract the heat of the high temperature gas leaking along the shaft 4 to shield the outboard bearing 6 from the high temperature of such gas. A second conduit 14 is shown as having its inlet end 15 opening into the discharge passage of the compressor and its outlet end opening into a lantern gland 16. The lantern glands 12 and 16 are of identical construction and are more clearly illustrated in the enlarged Figure 2. These lantern glands or distributors 12 and 16 have annular passages 17 formed in their outer perimeters into which the gas is delivered from their respective conduits 10 and 14. A plurality of radially extending circumferentially spaced openings 18 connect the annular passage 17 with an inner annular passage 19. The annular passage 19 formed in the distributor or lantern gland 16 extends about the shaft 4. If it is so desired 55 the inner surface of the lantern gland may be

serrated as shown at 20 to facilitate the distribution of the gas along and about the shaft 4.

If it is so desired, throttle valves of any approved type which may be purchased upon the open market, and shown at 21 in the drawings, may be interposed in the pipes or conduits 10 and 14 to permit regulation of the flow of the gas through those conduits.

While in the drawings the inlet of the pipe 10 is shown connected to the discharge of the first stage of the multi-stage compressor and the inlet of the conduit 14 is shown connected to the discharge passage of the compressor, it is to be understood that these inlets may be connected at any suitable stage or point within the compressor casing to provide tempering gas at the temperature desired and best suited to shield the respective bearings from the extreme temperatures of the compressor operation.

It will be understood that the invention is not to be limited to the specific construction or arrangement of parts shown, but that they may be widely modified within the invention defined by the claims.

What is claimed is:

1. In a centrifugal compressor including a casing having a suction inlet and a discharge outlet, an impeller shaft, an inboard bearing for said impeller shaft, an outboard bearing for said impeller shaft, of a conduit opening into said casing at a point in proximity to the suction inlet, a distributor on said shaft between said outboard bearing and the discharge of the compressor, said conduit opening into said distributor for delivering relatively cool gas from within the compressor casing to said distributor to form a temperature shield for said outboard bearing.

2. Means for shielding bearings of a centrifugal compressor from extreme temperatures of the compressor operating conditions which comprises in combination with a centrifugal compressor including a casing having a suction inlet and a discharge outlet, an impeller shaft, inboard and outboard bearings for said impeller shaft, of a conduit opening into said casing at a point in proximity to the discharge outlet of said casing, a distributor on said impeller shaft between the inboard bearing and the suction of the casing, said conduit opening into said distributor for delivering relatively hot gas from within the compressor casing to said distributor to form a temperature shield for said inboard bearing.

3. Means for shielding bearings of a centrifugal compressor from extreme temperatures of the compressor operating conditions which comprises in combination with a centrifugal compressor including a casing having a suction inlet and a dis-

charge outlet, an impeller shaft, inboard and outboard bearings for said impeller shaft, of a conduit opening into said casing at a point in proximity to the discharge outlet of said casing, a distributor on said impeller shaft between the inboard bearing and the suction of the casing, said conduit opening into said distributor for delivering relatively hot gas from within the compressor casing to said distributor to form a temperature shield for said inboard bearing, a second conduit opening into said casing at a point in proximity to the discharge outlet of said casing, a distributor on said shaft between said outboard bearing and the discharge of the casing, said second conduit opening into said second distributor for delivering relatively cool gas from within the compressor casing to said distributor to form a temperature shield for said outboard bearing.

4. Means for shielding bearings of a centrifugal compressor from extreme temperatures of the compressor operating conditions which comprises in combination with a centrifugal compressor including a casing having a suction inlet and a discharge outlet, an impeller shaft, inboard and outboard bearings for said impeller shaft, of a conduit opening into said casing at a point in proximity to the discharge outlet of said casing, a distributor on said impeller shaft between the inboard bearing and the suction of the casing, said conduit opening into said distributor for delivering relatively hot gas from within the compressor casing to said distributor to form a temperature shield for said inboard bearing, a second conduit opening into said casing at a point in proximity to the suction inlet, a distributor on said shaft between said outboard bearing and the discharge of the casing, said second conduit opening into said second distributor for delivering relatively cool gas from within the the the compressor casing to said distributor to form a temperature shield for said outboard bearing, and valves in said conduits for regulating the flow of gas therethrough.
